UNITED STATES PATENT OFFICE

HARRIS HANFLIG, OF CHARLESTOWN, MASSACHUSETTS.

LOCK.

1,071,913.

Specification of Letters Patent.

Patented Sept. 2, 1913.

Application filed September 28, 1912. Serial No. 722,894.

To all whom it may concern:

Be it known that I, HARRIS HANFLIG, a citizen of the United States, residing at Charlestown, in the county of Suffolk and 5 State of Massachusetts, have invented a new and useful Improvement in Locks, of which the following is a specification.

This invention relates to a combination trunk lock, the object of the invention being 10 to provide a simple and convenient lock adapted especially for attachment to trunks and similar packing boxes, or cases, whereby the same can be quickly opened without the use of a key, and at the same time be 15 surely locked against any party not familiar with the combination.

With this object in view, the invention consists of the novel features hereinafter described, pointed out in the claims and shown 20 in the accompanying drawings, in which,

Figure 1 is a face view. Fig. 2 is a section on the line 2—2 of Fig. 3. Fig. 3 is a vertical longitudinal section through the lock, parts being shown in locked position. 25 Fig. 4 is a detail section upon the line 4—4 of Fig. 3. Fig. 5 is an inner face view of a rotatable index plate. Fig. 6 is a perspective view of an arbor. Fig. 7 is a detail side elevation of one of the disks.

30 In these drawings, 1 represents the body portion of a trunk, box or case and 2 the usual hinged lid or cover intended to be locked in closed position with the body portion 1. The front face of said body portion 35 1 is suitably recessed as shown at 3 to receive the lock casing 4 and the mechanism contained therein. This casing may be of any suitable shape and design and I do not desire to be limited to any particular form of 40 casing for the locking parts, nor to any particular method for securing said casing or other parts to the trunk, box or casing. In the lower portion of this casing is mounted 45 an arbor 5 adapted for vertical movement in a slot 6 formed in the front face of the casing 4. This arbor has loosely mounted upon it a disk 7, provided with an outwardly projecting sleeve or hub portion 8 upon which is fixed a rotatable milled plate 9

50 carrying a suitable index or pointer 10. The disk 7 is radially slotted as shown at 11 and is also provided with an inwardly projecting pin 12. Preferably in order to facilitate changing the combination, I prefer to 55 form a plurality of threaded openings 13 in the disk 7 and also in a co-acting disk 14

which is mounted loosely upon the arbor. The disk 14 also carries a pin 15, and by threading the pins 12 and 15 they can be changed from one opening 13 to the other or 60 any number of these openings may be provided thus permitting many changes in the relative positions of the pins. The disk 14 is also radially slotted being similar in construction to the disk 7 and spaced by a suitable washer 16 from said disk 7. The pins 12 and 15 project from the adjacent faces of the disks and as said disks are rotated one pin is adapted to pick up the other.

A suitable stop 17 is arranged upon the 70 inner face of the casing 4 and immediately below the slot 6 said stop preventing downward movement of the arbor and the locking mechanism except when the radial slots 11 of the two disks are in horizontal alinement 75 with each other and at the same time register with the stop 17. A locking plate 18 is secured by a suitable nut upon the squared inner portion of the arbor and is angled and reduced in width throughout its upper portion to form a locking bolt 19 as shown in 80 Figs. 2 and 3. The opposite sides of the plate are split and bent to form hook members 20 to which the lower ends of the springs 21 are secured, the upper ends of 85 the springs being secured to suitable hooks 22 carried by the upper portion of the casing 4. These springs hold the arbor in the upper end of the slot 6 and also normally held said bolt in engagement with a suitable slot in a lug 23 carried by a hinged 90 spring pressed hasp 24. The hinged hasp 24 is carried by a suitable plate 25 which may be riveted or otherwise secured to the cover portion 2 of the trunk, which forms a 95 suitable ground or surface upon which the name of the owner of the trunk may be placed.

From the drawings and above description the operation of the device will be 100 clear. By turning the plate 9 with the thumb the disk 7 will be turned so that the pin 12 will pick up the pin 15 and rotate the disk 14 thereby bringing the radial slot 11 of said disk into registry with the stop 105 17. The direction of rotation is then reversed until the slot 11 of disk 7 has been brought into registry with the stop 17. Downward pressure of the thumb upon the plate 9 causes the arbor to move vertically 110 in the slot 6, thereby carrying the locking plate 18 and bolt 19 downwardly and dis-

engaging the bolt 19 from the lug 23 and permitting the hasp 24 to be swung outwardly into open position.

It will of course be understood that both 5 disks 7 and 14 turn loose upon the arbor and that the casing 4 is provided with a suitable opening through which the lug 23 works.

What I claim is:—

10 1. In a lock, a movable arbor, disks rotatably carried thereby and radially slotted, a stop adapted to normally limit sliding movement of the arbor, the said slots being adapted to register with each other and 15 with said stop, a hasp, and means carried by the arbor adapted to normally engage said hasp.

20 2. A lock comprising a hinged hasp, a casing, said casing having a suitable opening and also having a slot, a slotted lug carried by the hasp adapted to work through the opening of the casing, an arbor mounted to slide in the slot of the casing, a stop carried by the casing and in alinement with 25 said slot, rotatable disks mounted upon the arbor and radially slotted, pins carried by the adjacent faces of said disks and adapted to engage each other, and a locking bolt car-

ried by the arbor and adapted to enter the slot of said lug.

3. In a lock a casing having a slot and an opening in alinement therewith, a hinged hasp, means carried by the hasp for entering said opening, an arbor mounted in said slot and adapted to move therein toward 35 and away from the hasp, a locking bolt carried by the arbor adapted to engage the locking means carried by the hasp, springs adapted to hold said arbor normally in the end of the slot adjacent the hasp, rotatable 40 disks mounted upon the arbor, a lug carried by the casing and in alinement with the slot, pins carried by adjacent faces of the disks, and means arranged upon the outside of the casing and connected to one of said 45 disks for the purpose of rotating the same, said disks being provided with radial slots, thereby adapting them to straddle the stop lug when said slots are brought into registry with each other and also into registry 50 with said lugs.

HARRIS HANFLIG.
